CLAIM

The ornamental design for a vehicle wheel rim, as shown and described.

DESCRIPTION

1. Vehicle wheel rim

1.1 is a front perspective view of a vehicle wheel rim showing my new design;

1.2 is a front elevation view thereof;

1.3 is a rear elevation view thereof;

1.4 is a right side elevation view thereof;

1.5 is a left side elevation view thereof;

1.6 is a top plan view thereof; and

1.7 is a bottom plan view thereof.

The broken lines shown are for the purpose of illustrating portions of the vehicle wheel rim and form no part of the claimed designs.
